US00D796480S

(12) **United States Design Patent** (10) Patent No.: **US D796,480 S**
(45) Date of Patent: ** Sep. 5, 2017

(54) **SPEAKER**

(71) Applicant: **LG ELECTRONICS INC.**, Seoul (KR)

(72) Inventors: **Yunhwan Sung**, Seoul (KR); **Gangho Woo**, Seoul (KR)

(73) Assignee: **LG ELECTRONICS INC.**, Seoul (KR)

(**) Term: **15 Years**

(21) Appl. No.: **29/551,593**

(22) Filed: **Jan. 14, 2016**

(30) **Foreign Application Priority Data**

Jul. 14, 2015 (KR) 30-2015-0035239

(51) **LOC (10) Cl.** **14-01**

(52) **U.S. Cl.**

USPC **D14/214**; D14/211

(58) **Field of Classification Search**

USPC D14/168, 188, 194, 195, 196, 204, 210, D14/211, 212, 213, 214, 215, 216

CPC B60R 11/0217; G06F 1/1688; G10K 9/22; G10K 11/004; H03F 1/327; H04M 1/03; H04M 1/035; H04N 5/642; H04N 21/4852; H04S 3/00; H04S 7/30; H04R 1/02; H04R 1/06; H04R 1/021; H04R 1/025; H04R 1/026; H04R 1/028; H04R 1/105; H04R 1/323; H04R 1/403; H04R 1/2803; H04R 1/2834; H04R 5/02; H04R 7/20; H04R 9/06; H04R 9/025; H04R 2201/021; H04R 2400/00; H04R 2400/07; H04R 2499/11; H04R 2499/13; H04R 2499/15
